APPARATUS FOR RECUTTING HELICOIDAL GEARS

William F. Zimmermann, Maplewood, N. J., assignor to Gould & Eberhardt, Newark, N. J., a corporation of New Jersey

Application April 16, 1932, Serial No. 605,641

14 Claims. (Cl. 90—4)

This invention is directed to a method for re-cutting helicoidal gears and an apparatus capable of effecting such method.

Despite certain recognized advantages of helical gearing its use in the past has been considerably curtailed by the inability on the part of manufacturers to commercially and economically produce helical gears which would operate with satisfactory quietness. Witness, for example, the 10 fact that many manufacturers of auto engines have found it preferable to employ a chain and sprocket drive rather than intermeshing helical gears for the timing gear drive; or have resorted to such expedients as the interposition in the 15 gear train of a non-metallic gear, all primarily in the interests of quietness and smoothness of operation.

The present invention is of especial importance in the manufacture of certain types of improved auto transmissions, such as the synchromesh, employing helical gears in which environment the degree of quietness is of the utmost importance. The invention is further important in its effectuation of economies, it being a primary 20 object to greatly reduce the manipulations and time consumed in the complete operation of producing the gear teeth; while at the same time attaining an uniformity of tooth spacing and correctness of tooth form sufficiently accurate to satisfy the most exacting requirements 25 in commercially employed gears.

As a fundamental of gear cutting it may be noted that it is practically impossible to commercially produce a gear from a finished blank 30 in a single cutting operation, which gear adheres sufficiently close to the specifications as to be satisfactory for such uses as those referred to. It has been found necessary, therefore, to first cut the gear spaces to the approximate size, 35 and follow this with a light finishing operation.

As a practical matter, however, the finishing or re-cutting of helicoidal gears on a large scale has presented a difficult problem. The desired standards of accuracy and finish are obtained 40 when there is but .005 to .010 inch of metal to be removed from the tooth sides. To remain within the limits of allowance, wherein some metal is removed over the entire tooth profile as the 45 hob cutter teeth progress down the helical grooves of the gear, but at no point causing the hob to be burdened with the taking of more than a light cut, requires an initial setting of the hob and gear blanks and the maintenance 50 of certain definite relations, the smallest devia-

tion from which would result in an inaccurate gear within the standards desired.

Due to the difficulty heretofore experienced in establishing a sufficiently accurate set-up, once the gear blanks have been removed from the arbor upon which they were rough-cut, various methods have been developed and employed for re-cutting helical gears on the same machine at the completion of the roughing operation retaining the same setting of the gear blanks on their spindle. These methods have varied considerably dependent in large part upon the type of machine and the adjustments which individual inventors have been able to develop and apply thereto. 10

Aside from the fact, however, that these prior methods require the exercise of considerable skill, and are, in many instances, time-consuming and inefficient; they are subject to a further and major disadvantage of being impractical in attempting to intermittently utilize the same machine and cutter for both roughing and finishing operations. In accordance with the present invention the gear blanks may be roughed out with a roughing hob on any type of machine 20 designed to withstand the severe operating conditions attendant upon the initial and major cut. The roughed out blanks are then set up and re-cut on a precision machine equipped with an especially accurate hob. Under the relatively 25 less strenuous conditions of the re-cutting operation the re-cutting machine and its hob may be maintained in superior condition resulting in exceptionally accurate, uniform helical tooth spaces and a fine smooth finish. The resultant 30 is not only an improvement in quality but a reduction in expense through the distribution of the roughing operations over a roughing or 35 cheaper cutter than the finishing cutter.

A full appreciation of this invention requires 40 a consideration of the characteristics of a hobbing operation and of hobbing machines of which there are two general types, referred to in the art as differential and non-differential machines. The former type is exemplified by such machines 45 as those disclosed in the patents to Pfauter #640,728 or Waterman #1,364,597; and the latter or non-differential type by the patent to Eberhardt and Zimmermann #1,028,815 or Zimmermann #973,399. Each type is provided with a 50 transmission which operates to produce three primary movements, namely the rotation of the hob, the rotation or continuous indexing of the gear blank, and the relative translation or feed between the hob and gear blank. Also the three drives 55

- must be positively inter-connected whereby, during cutting operation, a predetermined relation will be unvaryingly maintained to result in a gear of uniform and accurate character.
5. There is, however, a distinctly fundamental difference between differential and non-differential hobbing machines. In the case of differential hoppers one of the aforementioned motions of rotation during cutting operation is the resultant of two component motions, one of which is derived from the feed drive mechanism. These two component motions combine through a differential mechanism to produce the required resultant rotary motion. The characteristics of such an arrangement are best illustrated by noting the effect upon the corresponding rotary motion when the feed is rendered operative or inoperative. Assuming the machine to have been properly adjusted as to ratios for a particular hob and helical pitch on the gear, then with the machine in operation and the feed disconnected the gear will continuously index and the tooth spaces thereof maintain a proper registration with the hob helix. If the feed is then connected the rotation of the hob or gear, as the case may be, will be continuously modified compatibly with the feed to produce the desired helix on the gear.
- With a non-differential machine, however, each drive train, though deriving its original motion from the same primary source and being thereby positively connected, is otherwise independent of the other two. The effect of this is that with the hob and gear in registration the feed cannot be independently stopped without the hob thereupon milling away the gear teeth. This characteristic is particularly noticeable in attempting to establish the initial setting for a recutting operation of helical gears. In such manipulation with a non-differential machine the hob cannot be brought manually into any degree of registration with the gear and allowed to rotate with the power feed disconnected without the hob gradually milling into the teeth of the helical gear.
45. An outstanding net result and distinguishing characteristic, therefore, between a setting operation for re-cutting helical gears in a differential machine and in a non-differential machine, and one which renders such operation particularly difficult in the latter type, resides in the fact that with a differential machine the hob and gear may be positively secured in position and the correct initial relation established through independent manual adjustment of the feed. With 55 a non-differential machine, however, the three drives are so related as to necessitate the simultaneous adjustment of two of the relations to achieve the correct initial setting.
- The present invention is particularly advantageous in being applicable to hobbing machines of the non-differential type, and enables helicoidal gears, which have been previously rough-cut on a machine of whatever type, to be finished or re-cut on such non-differential machine with extreme facility and precision. The organization specifically disclosed herein, therefore, is a non-differential machine in general and the method is described as achieved with such type machine.
- The apparatus, as depicted in the drawings, includes a transmission system capable of imparting the proper compatible motions to the hob and gear blanks. As a primary feature of the organization the transmission branch for effecting the relative translation between the hob and gear blanks has an electively separable driving

connection interposed therein capable of being disconnected to permit of a desired independent linear adjustment between the hob and gear blanks and then re-engaged. The proportioning of the ratios and driving elements, and the arrangement in general is such that the re-engagement may be effected without disturbing the previously manually effected setting to any substantial degree, such as would be the case with an ordinary coarse tooth positive clutch, for example. As disclosed the electively separable connection comprises an auxiliary clutch in the transmission line operating to translate the hob carrying head. The clutch itself is fine-toothed and accompanied by a location and proportioning of driving elements such that, if in making the manual set-up the teeth should be displaced the maximum angular distance possible between two adjacent inter-engaging positions, the subsequent engagement will result in but very little displacement of the hob head, and thereby the adjusted relation of the hob with respect to the gear blanks. The particularly practical advantage of this is that but a minimum amount of material need be left on the roughed out gear blanks for removal in the re-cutting operation.

A further very important and co-related function afforded by the machine organization of this invention resides in the provision of means, peculiarly effective in the type of organization shown, for the removal of back-lash from the drive trains, thereby eliminating, as far as possible, the indeterminate, but frequently very serious, departure from the correct relation, should an ultimate driven element be delayed in picking up the corresponding motion from a particular transmission branch containing back-lash, while other motions to the gear blank or hob had been immediately initiated.

The more specific features of the method and of the machine organization will be taken up in greater detail hereinafter in connection with the description of the drawings, from which it will be apparent that the present invention will enable one to re-cut a gear, or a stack of gears, that have been previously roughed on another machine and/or by some other process. Further, that such operation may be performed in an economical and rapid manner; and that from the close initial setting, which may be originally attained and subsequently maintained through the complete re-cutting operation, but little stock need be left in the roughed-out tooth spaces for removal on the finishing cut whereby the final tooth form, spacing and finish will satisfactorily comply with present exacting requirements.

The more specific objects and advantages will be indicated in part or rendered apparent from the hereinafter description.

To enable others skilled in the art so fully to apprehend the underlying features that they may practice the method and compound a suitable machine therefor, in accordance with the various ways contemplated by this invention, drawings depicting a preferred typical construction have been annexed as a part of this disclosure and, in such drawings, like characters of reference denote corresponding parts throughout all the views, of which:—

Figure 1 is a general organizational view in elevation of a hobbing machine containing an arrangement of operating parts, in accordance with this invention. Fig. 2 is a fragmentary elevation taken on the opposite side of the hobbing machine from Fig. 1. Fig. 3 is a fragmentary view

depicting in particular the auxiliary fine-tooth clutch contained in the drive to the hob carrying head. Fig. 4 is a front elevation of the entire machine. Fig. 5 is a view of the hob slide and universal table carrying the hob spindle. Fig. 6 is a cross sectional view showing details of the drive for rotating the hob spindle. Fig. 7 is a view similar to Fig. 5 but with the universal table removed to show better certain details. Figs. 8 and 9 are fragmentary cross-sectional views of details of the hob slide. Fig. 10 shows an alternative mechanism for operating the auxiliary fine-tooth clutch of Fig. 3. Fig. 11 is a view largely diagrammatic and showing in clearer manner the complete transmission. Fig. 12 is a detail view of certain manual control levers exhibited more generally in the assembly view of Fig. 11.

The general arrangement of the particular hobbing machine illustrated herein is similar to that disclosed in my prior Patent #1,625,581 and includes a bed B upon which is mounted the upright tool support S horizontally adjustable along the bed on the ways 10; and a work spindle W supported in large bearings in the bed B. The work spindle occupies a fixed position at the forward end of the machine where it remains conveniently accessible at all times for the application or removal of gear blanks, and being non-translatable, enables the work spindle to be very rigidly mounted in a solid support free from vibration under the stresses normally imposed thereon.

The stanchion S is of considerable extent in horizontal cross sectional area providing a large base area contacting with the ways 10 of the base B providing a very substantial support fully capable of effectively resisting the turning moments resulting from the pressure on the hob while in engagement with the work. The stanchion S in turn carries a universal cutter slide or head H translatable on the vertical ways 11 on the forward face of the stanchion. The head H includes a supporting bracket 12 which is adapted to be swivelled on the base portion 13 of the head and clamped in position through the medium of bolts having their heads engaging in the circular T-slot 15 of the base portion 13. The bracket 12 is provided with a hob spindle 16 carrying the hob cutter C rotated through mechanism to be later described in greater detail.

The power drive for the entire machine proceeds from the pulley P adapted, as shown, to be driven from any suitable primary source, or which pulley may exemplify in itself an electric motor forming a part of the machine tool entity. The pulley P is adapted to be electively clutched to drive the main shaft 17 through manipulation of the sliding key 18 connected to the collar 19 operable from the manual lever 20 having a forked end provided with trunnions tracking in a recess of the collar 19. The drive, during working operations, when a predetermined relation must be maintained between the several elements, is derived from the main shaft 17. An auxiliary and alternative drive for producing independent rapid traverse movements of the head H is provided through mechanism including the parallel shaft 21 which will be again referred to and described as to detail.

Three branch transmission lines proceed from the main shaft 17, one for rotating the work-carrying spindle W; another for rotating the hob spindle; and a third for feeding the head H carrying the hob spindle. These can be most readily observed by reference to Fig. 11. The successive

elements in the work rotating branch comprise a gear 22 on the end of shaft 17 meshing with a gear 23 which has integral therewith a bevel gear 24 mating with a bevel gear 25 secured on the long shaft 26. As shown at the left in Figs. 1 and 11 the shaft 26 carries a spur gear 27 which drives a spur gear 28. A spur gear 29 is formed with gear 28 to rotate therewith and drives a larger gear 30 fixed on the long shaft 31. A worm 32 secured, or formed, on shaft 31 drives a worm gear 33 secured on the lower end of the work spindle thereby completing the drive for slowly rotating the work spindle W carrying one or more blanks W'.

The hob rotating transmission will next be described. The stanchion S carries a vertical splined shaft 36 mounted in an upper bearing 37, and a lower bearing 38 in a bracket 39 secured to or formed with the stanchion S. A gear 40 likewise supported in the bracket 39 is splined on the horizontal shaft 26 and meshes with a bevel gear 41 secured on the lower end of the shaft 36. This constitutes an adjustable drive for the vertical shaft 36 carried by stanchion S enabling the stanchion to be adjusted along its supporting ways on the base B. Carried in suitable bearings in the base portion 13 of the slide H is a bevel gear 42 splined on the vertical shaft 36. A shaft 43 (Figs. 5 and 6) supported in bearings in the base 13 carries a bevel gear 44 engaging with the bevel gear 42. The base 13 also carries a short transverse shaft 45 supported in bearings 46 and 47 (Fig. 6). Formed on the shaft 45 or secured thereto is the worm gear 48 meshing with the worm 49 on the shaft 43. A bevel pinion 50 is also carried by shaft 45 integral with worm gear 48. End thrust on the shaft 45 is provided for by the ball thrust bearings 51 and 52 respectively. The shaft 43 extends through the base 13 to the right as shown e. g. in Figs. 5 and 6. This outer end is provided with a nut 43a rendered non-rotatable with respect to shaft 43 by locking pin 43b. The particular advantage of this construction will be subsequently described but for the present it may be noted that it enables the application of a wrench thereto for rotating the drive mechanism backwardly.

A shaft 55 is carried in suitable bearings in the swivelable bracket 12 including the end ball bearing 56 engaged by and adjustable as to position by the nut 57. This shaft carries a bevel gear 58 at its inner end mating with the bevel gear 50; and a spur pinion 59 at the outer end engaging with a larger spur gear 60 secured on the hob cutter spindle to rotate the latter. It will be observed that the shaft 55, including its gear 58, is carried by the swivelable bracket 12 whereas the driving gear 50 is carried by the base 13, the axis of the latter being coincident with the axis of the bracket 12, thereby enabling the bracket to be readily rotated to vary the direction of the hob axis in accordance with the variable factors of the helix angle of the hob and the gears to be formed.

The third transmission line, serving to feed the hob slide H, proceeds from the long shaft 31 mounted in the bed. For this purpose a bevel gear 63 secured thereon drives a bevel gear 64 secured on the shaft 65 which shaft is likewise carried in bearings in the bed B. Another short shaft 66 mounted in the bed B has a worm gear 67 thereon engaging with the worm 68 on the shaft 65. A spur pinion 69 on the shaft 66 meshes with gear 70 of an idler gear set which

includes the gear 71 meshing with gear 72 fixed on a sleeve 73 rotatably mounted on the shaft 74. The sleeve 73 is slideable longitudinally of the shaft 74 and may be clutched thereto to drive the shaft through the intermediary of a clutch jaw on the inner end of the sleeve 73 adapted to be electively engaged through manually operative means with a complementary clutch jaw secured to the shaft 74, the clutch as a whole being indicated at 75.

The subsequent elements in the transmission drive to the feed are mounted in the stanchion S to move therewith and include a bevel gear 78 mounted in a suitable bearing provided by a bracket 79 secured to the lower portion of the stanchion. The gear 78 is splined on the horizontal shaft 74 thus permitting adjusting of the stanchion along its ways. A bevel gear 80 mates with gear 78 and has a sleeve extension 81 rotatably mounted on the vertical shaft 82 and in the fixed bearing 83 of the stanchion. End thrust of the gear and sleeve is provided for by a lower bearing 84. A collar 85 secured to the sleeve 81 prevents movement in the opposite direction. The gear 80 is adapted to be clutched to the shaft 82 to drive the latter through the medium of a fine tooth clutch indicated as a whole at 86, the more specific purpose and details of which will be later described.

The vertical shaft 82 is of considerable length extending to near the top of stanchion S, and has the spur gear 87 secured thereto at that point meshing with a spur gear 88. Gear 88 is mounted in a solid cross bar 89 of the stanchion S and includes as a unit an internal nut cooperating with the non-rotatable threaded feed shaft 90, the lower end of which shaft is secured at 91 to the slide H. Rotation of the gear and nut 88, therefore, serves to raise or lower the slide H as the case may be.

The transmission just described constitutes the feed for the slide and normally is at a slow rate and in but a single direction (down). An auxiliary drive is provided, however, adapted to be injected into the train of mechanism as desired to rotate the gear and nut 88 at a more rapid rate, and in either direction, to thereby produce a corresponding rapid traverse of the head H either up or down as the case may be. This rapid traverse drive is derived from the gear 94 integral with, or secured to, the pulley P, and is, therefore, independent of the clutch controlled shaft 17. Gear 94 meshes with gear 95 mounted on shaft 21 carried in the bed A, the opposite end of shaft 21 carrying a bevel gear 96 engaging with opposed bevel gears 97 and 98 normally freely rotatable on the shaft 74 but adapted to be selectively clutched to the shaft 74 through shifting of the clutch collar 99 into engagement with the opposed clutch teeth formed on the respective gears 97 and 98 complementary to the teeth on the clutch collar. As will be pointed out more in detail an interlocking control mechanism is provided, whereby clutch 75 controlling the slow feed and the clutch 99 controlling the rapid traverse, cannot be made concurrently effective. An impositive drive to the shaft 21 also may be incorporated in the transmission line comprising a friction plate connection between the gear 95 and the shaft 21, the gear 95 being clamped between plates 95a keyed to the shaft 21.

A means for moving the slide H manually is also provided comprising a hand wheel 102 carried by shaft 103 mounted in the stanchion S which shaft at the opposite end also carries a bevel

gear 104 mating with a gear 105 secured on the shaft 82. The manual adjusting means just described has a particular and important function in setting up the machine for the recutting of gears, as will be pointed out.

At infrequent times the stanchion S must be adjusted forward or back on its ways as, for example, when gear blanks of different diameter are to be operated on. A manually operative means for this purpose is provided comprising a feed screw shaft 108, one end of which is rotatably secured in a bearing 109 in the stanchion S and the opposite end of which threads into a nut 110 fixed in the bed A. A cross shaft 111 mounted in the stanchion S has a hand wheel 112 affixed to its outer end; and a helical gear 113 affixed to its inner end which gear mates with a companion gear 114 splined on the shaft 108. Rotation of hand wheel 112, therefore, will serve to translate the stanchion S along its ways.

The manual controls for the various clutches and the interlocking means for preventing incompatible operation thereof to the injury of the machine or work will now be described. The details thereof are, for the major part, identical with those illustrated in my prior Patent #1,625,581, to which reference may be made for a fuller disclosure as to certain specific details. In the interest of convenience, however, the elements, for the most part, will be described herein. As previously noted the master clutch within the pulley unit P is controlled from the lever 20. Upward movement of lever 20 in Fig. 11 engages the clutch. The lever is continuously urged downward, as shown in this figure, to its declutching position, by a spring pressed plunger 117 bearing against a projecting finger 118 rigid with the lever 20. When engagement of the clutch is effected, however, a latch 119 secured on the shaft 120 hooks over a second finger 121, rigid with lever 20, and locks the latter in its clutching position. A releasable spring pressed plunger holds the latch 119, and thereby the lever 20, in this position until released manually or automatically by partial rotation of shaft 120. Manual rotation of shaft 120 is effected from the hand lever 122 secured thereto; and by automatic means through movement of lever 123, likewise secured to the control rod 120. A rod 124, extending vertically alongside the stanchion S, is pivoted to the lever 123. This vertical rod carries an adjustable stop 125 which is adapted to be engaged by dog 126 secured to the slideable head H. Such engagement will, through linkage just described, trip the latch 119 and permit plunger 117 to move the master clutch to its disengaged position, thereby determining the limit of downward feed.

The linkage mechanism for operating the rapid traverse clutch sleeve 99 comprises an oscillatable shaft 128 to which is secured a finger 129 projecting into an annular groove in the clutch sleeve; and a bevel gear 130 secured to the opposite end of shaft 128 and meshing with a bevel gear 131 secured on an oscillatable shaft 132, to which shaft is also secured oppositely projecting levers 133 and 134 for manual and automatic operation respectively.

The automatic feature is operative to move the clutch 99 to neutral at appropriate points in the travel of the head. The mechanism therefor includes, in addition to that just described, a vertically extending rod 135 pivoted to the lever 134 at the lower end of the rod; and a bell crank 136 pivoted to the stanchion S at 137 and having

one arm pivoted at 138 to the upper end of rod 135 and the other arm adapted to contact with a cam plate 139 secured to the translatable head H. In the position of bell crank 136 shown in Fig. 5 2 the clutch 99 is in neutral. In addition to cam plate 139 dogs 140 and 141 are provided, adjustably secured to the vertical rod 135.

The operation then would be somewhat as follows: Assuming the head H to be in its normally uppermost position the cam plate 139 would be elevated from the position shown in Fig. 2 and the arm 142 free from contact therewith. To initiate a downward rapid traverse, the operator would depress the lever 133 engaging the clutch 159 with the appropriate gear; raising vertical rod 135; and rotating bell crank 136 clockwise in Fig. 2 to bring arm 136 into the path of cam plate 139. As the head proceeds downwardly the inclined edge 143 of the cam plate will engage arm 142 camming the bell crank 136 to the position of Fig. 2 and throwing the rapid traverse clutch to neutral. The controls would normally be so adjusted that the hob has approached reasonably close to the work and in position for the initiation of the slow feed. As the slow feed proceeds the arm 142 continues to ride along the straight edge 144 of the cam plate 139. For rapid traverse reverse the corresponding manual shifting of clutch 99 will have been moved clockwise a certain angle from the position shown in Fig. 2. The stop 141 will serve as a means to return the clutch to neutral if the reverse movement is allowed to proceed until such stop is engaged by plate 126. The stop 140 likewise acts as an auxiliary safety device to limit downward rapid traverse.

There is yet to be described the operating and control means to the feed clutch 75. This is accomplished through the oscillatable control rod 40 145 (see Fig. 11) to which is secured at one end the manual lever 146 and at the other end bevel gear 147 meshing with bevel gear 148 on the control shaft 149. The end of shaft 149, adjacent clutch 75, is preferably provided with an impulsive clutch operating connection comprising a finger 150 loosely mounted on shaft 149 and adapted to float between the projecting ears 151 and 152 rigid with the shaft 149. Ear 152 carries a spring pressed plunger 153 adapted to bear against the finger 150. In the event, therefore, that the opposed clutch teeth are not correctly positioned for instantaneous inter-engagement upon manipulation of lever 146, a delayed engagement will occur. Preferably also a detent means 55 is provided for ensuring complete movement of the clutch 75 to either extreme position and maintaining it in such position except upon intended shifting thereof. Any well known device for this purpose may be employed, such as that shown in my Patent No. 1,625,581 referred to above.

As shown in Fig. 12 an interlock is provided for preventing the feed clutch 75 and the rapid traverse clutch 99 being concurrently engaged through inadvertent manipulation or accident. Secured on the control shaft 145 to the feed clutch 75 and integral with the control lever 146 is the projecting finger 155 carrying the V-shaped lug 156. The lever 133 on control rod 132 to the rapid traverse clutch 99 has integral therewith a ledge portion 157 with which the lug 156 is arranged to cooperate. The ledge is provided with a V-shaped depression 158 positioned between the high portions 159 and 160. In the position shown in Fig. 12 lever 133 is in mid-position and its rapid traverse clutch in neutral. The lever 146, how-

ever, has the lug 156 engaged in the depression 158 and the lever 146 is in its lower position wherein feed clutch 75 is in engagement. If lever 133 is moved to either extreme position, as shown in broken lines in Fig. 12, the lug 156 will ride on the cam portion 159 or 160 as the case may be and lever 146 moved to its upper position, shown in broken lines in Fig. 12, and the feed clutch 75 accordingly disengaged.

A universal cutter slide is incorporated in the machine presenting advantageous features with reference to its manner and range of adjustability; and means for firmly maintaining it in adjusted position. The hob spindle bracket may be rotated on its base 13 through an angle of 180° 10 and more, which necessarily satisfies any condition of operation presented by the various types of gears and the variation in the helix angle of the hob and gears. As shown in Fig. 6 the hob spindle supporting bracket 12 is provided with an annular flange 161 adapted to project into a circular bearing 166 of the base 13. In addition ample plane bearing surfaces are provided on the base 13 against which corresponding surfaces of the bracket 13 bear forming a rigid metal to metal 15 contact when the heretofore mentioned bolts 14, 20 engaging in the T-slots 15, are drawn up.

Angular adjustment of the bracket 12 about its axis is conveniently accomplished through the application of a wrench to the projecting 30 squared end 167 of the shaft 168 supported in bearings 169 and 169' of the bracket 12. Shaft 168 carries a worm 170 which bears at one end against a collar 171 encircling the shaft 168, in turn bearing against a washer 172 supported by 35 the outer bearing sleeve 169 secured in the bracket 12 by machine screws 173. Thrust in the opposite direction and also axial adjustment is provided for by the outer collar 174 threaded on the shaft 168, and compound washers 175 and 40 176 inserted between the collar 174 and bearing sleeve 169.

Worm 170 meshes with worm gear 177 of the stub unit 178 having the small and large bearing 179 and 180 respectively in the bracket 12. 45 The stub unit 178 also carries the small spur gear 181 which meshes, in assembled position, with the ring gear segment 182 secured to the base 13 co-axial with the shaft 45 as shown particularly in Fig. 7. Rotation of the shaft 168, 50 therefore, causes the gear 181 to roll around the gear segment 182 and the bracket 13 to be angularly adjusted about its axis in a corresponding manner.

Suitable graduated means for indicating the 55 angularly adjusted position may be provided, comprising, in the specific form here shown, a thin arcuate plate 185 imbedded in the base 13; and a small plate 186 secured to the bracket 12 to move adjacent the plate 185, the two having appropriate indicia to which the angular position of the bracket 12 can be referred.

The cutter arbor is supported on the frame 12 between the opposed bearing members 187 and 188, the former constituting the driving end. 65 Each of these bearing members is axially adjustable to suit the particular hob and arbor, the bearing member 188 being held on its supporting surfaces by cleats 189, and bearing member 187 by cleats 190. Axial adjustment of bearing member 187 is produced through rotation of the nut 191 threaded on and pinned to the shaft 192, the exact details of the connection, not being of importance to the present invention, are not shown. The arbor holder 193 is secured to and 70 75

driven from the shaft 194 splined in the gear 68 which is rotated through the train of mechanism heretofore described.

In the foregoing description an auxiliary clutch 5 86 has been noted in a general way. This clutch, it will be seen, is interposed in the drive for translating the hob carrying slide. The peculiarly unique and important function of this clutch, in its association with the general machine organization, will now be described, together with 10 certain details of construction.

The clutch 86 may be disconnected, as desired, through the medium of hand lever 195 (Fig. 2) secured on shaft 197, the opposite end of 15 which shaft has a lever 198 secured thereto carrying a pin 199 tracking in annular groove 200 of the sleeve 201 splined on the shaft 32. To hold the clutch 86 in disengaged position a latch 202 is provided having a hook 203 adapted to 20 engage under a pin 204 secured in the handle 196.

Fig. 10 shows a modified form of manual clutch operating means in which an eccentric pin 205 is mounted on the shaft 197 and projects into the annular groove 203 of the clutch sleeve 201. 25 As the handle 196 is swung 180 degrees the clutch becomes self-locking in either engaged, or disengaged position, as the case may be.

With the clutch 86 disconnected the hob carrying slide may then be raised or lowered by rotation of the hand wheel 102. For a particular purpose, to be described presently, the hand wheel 102 carries graduation marks 205 on the hub thereof arranged to be referred to the zero mark 207 on the fixed supporting bearing 208.

With the understanding of the physical embodiment of the invention gained from the above description, its adaptation to the method of the invention, and the method itself, will be reviewed somewhat in detail.

It is assumed that we have a group of helical gear blanks in which the teeth have been roughed out on some conventional machine. In view of the accuracy of setting, which may be initially effected and maintained with the present machine, the roughing operation may have been carried to the point of bringing the gear teeth size and shape very closely to the ultimate finished dimensions. In this respect it may be noted that the best finish and accuracy of spacing and tooth form is obtained when only .005 to .010 inch of material is required to be removed from the sides of the teeth on the finishing operation. The method of finishing or recutting these roughed gears then consists, in accordance with this invention, of placing one or a stack of these gear blanks on the work arbor of the machine illustrated. The gear blanks at this stage are not clamped on the arbor but are left free enough to be independently rotated. It is to be understood 55 that the machine has been provided with the proper hob and that the proper angle for the hob arbor has been established through adjustment of the universal table which, as shown, is of a type to render this readily obtainable and adaptable to any conditions which would be encountered. Also the required gear ratios to impart compatible motions to the hob and gear will have 60 been established.

The initial machine operation, after the gear 70 blanks have been mounted on the arbor, will be to bring the cutter slide downward to locate the cutter closely adjacent the initial cutting position. This is accomplished, of course, through the traverse clutch 99, the main feed clutch 75 being at this time disengaged. Feed clutch 75

is then engaged. Following this, hand wheel 102 is rotated backward, i. e. against the normal down feed to take up the back-lash between it and the feed clutch which has just been engaged. This reverse rotation is slight insofar as observable movement is concerned, but is, nevertheless, important in that it removes all back-lash in the feed train and contacts the driving surfaces. The re-setting clutch 86 is then disconnected permitting the cutter slide to be manually lowered or 10 raised by the hand wheel 102. Through oscillation of the hand wheel the hob is maneuvered into exact registration with the uppermost gear blank teeth. It is to be remembered that the gear 15 blanks are loose on the work spindle and two independent motions are thus permitted. That is, the hob may be vertically translated and the gear blanks rotated. In conjunction with the operation of lowering the hob and oscillating the gear blank, the present method contemplates further 20 means for the achievement of an initially accurate setting and the preservation thereof upon the institution of the power operation. This consists of the step of rotating the hob and its drive mechanism in a reverse direction, which may be accomplished, in the particular hob slide construction shown, through the application of a wrench to the 25 nut 43^a on the conveniently projecting end of shaft 43. In practice the same wrench used for the cutter spindle clamping nut may be employed 30 for this operation, these two nuts being made identical for that purpose. If a reversible gear connection is utilized in place of the gears 48 and 49 such backward operation of the hob and drive mechanism may, in fact, be through application 35 of the wrench to the cutter spindle clamping nut 16^a. It will be apparent that this reverse rotation of the hob serves to remove all back-lash and to bring all driving faces into contact in the corresponding drive train just as in the case of the 40 feed mechanism to which reference was made above. Accordingly, there is eliminated the factor of delay in picking up the corresponding motion upon the initiation of the power drive while the other one or more motions had materially progressed. Accuracy of initial setting is 45 thereby preserved, and danger of broken cutters or of damaged gears is obviated, as will perhaps be more apparent from a consideration of the entire method, the further steps and features of 50 which will now be continued.

The steps thus far related result in the hob teeth being set exactly into the adjacent roughed out helicoidal gear tooth spaces, and the proper three-fold relation between the hob and uppermost gear blank accurately established. If several gear blanks are mounted on the work arbor, as would usually be the case, the lower ones may be accurately lined up in succession from the uppermost one in engagement with the hob, 60 through the use of a suitable pin or wire in the gear blank tooth spaces, and the stack, as a whole, then firmly clamped in position.

After the proper registration of the hob and gear blank has been established the re-setting 65 clutch 86 is engaged and the machine is ready to start on its finishing cut. A feature of prime importance, in connection with this clutch and its co-related drive mechanism, should be here noted. This auxiliary electively separable connection between the cutter slide and the normal power drive may assume various forms, an essential characteristic being that of enabling the power drive to be established without disturbing the setting of the hob with respect to the gear 70 75

blank to any material degree. The permissible variation depends upon the particular circumstances but it may be noted, in general, that it must be within the allowances of material left for finishing purposes on the gear blank teeth. In this respect it is further noted that best finishing results are obtained when but .005 to .010 of an inch are removed on the finishing cut. A further essential characteristic of this separable drive connection is the requirement that the connection, when effected, must constitute a positive non-slipping drive.

The mechanism shown includes the resetting clutch 86 which has been heretofore referred to, somewhat in general; but an important feature thereof, which should now be specifically noted, is that the inter-engaging teeth are closely arranged constituting what is termed a fine-tooth clutch. The exact spacing and number of teeth may vary, dependent upon circumstances and the mechanical ratios between subsequent elements in the drive train. A clutch with 24 teeth in conjunction with the gear ratios and arrangement shown, has been found entirely satisfactory. The number of graduations 206 equal the number of clutch teeth, and the stationary zero line 207 in conjunction with the graduations indicates the position of the re-setting clutch teeth one to another. Also, each graduation or one tooth of the clutch is equivalent to .005 of an inch in vertical movement of the cutter.

The particular construction for this auxiliary selectively separable connection, exemplified by the clutch 86, is to be understood as illustrative only, and the term fine-tooth clutch, as used herein, including the claims, is intended to generically refer to a means for disconnecting the drive and positively re-establishing the drive at will, the arrangement being such that the re-engagement may be effected without requiring, in any single instance, more than a small angular adjustment between the complementary members to completely establish a positive drive therethrough.

With the above comprehensive description of the construction and function of the re-setting clutch 86 the further steps constituting the method of re-cutting helicoidal gears in its complete aspect may now be more conveniently described. Immediately upon the beginning of the operation under the machine power, observation should be made to determine whether the hob is cutting uniformly on each side of the teeth. As has been previously noted, it is desirable that a minimum of material be left for finishing operation which necessitates, however, a very close adjustment of the hob with respect to the gear. If upon the observation noted it appears that the hob is not cutting uniformly the next step is to stop the machine; disconnect the re-setting clutch 86; and manually move the cutter slide up or down, as the case may require, paying attention to the amount indicated by the graduations 206. The re-setting clutch can then be re-engaged and normal power operation of the machine resumed.

The setting-up operation requires but a fraction of the time necessary to give an explanation thereof, and can be accurately accomplished by an ordinarily skilled operator. The fine degree of adjustment available, together with the capability of the elimination of back-lash, as is possible in the arrangement shown, result in a non-differential hobbing machine capable of ready application to the re-cutting of helicoidal gears; and further capable of the production of heli-

coidal gears of the utmost perfection and precision.

With the back-lash removed, through the means provided, assurance may be had that the related motions of work rotation, hob rotation, and hob translation will be simultaneously and instantaneously initiated upon engagement of the main clutch. The instrumentalities for removing the back-lash, it will be noted, are connected into the corresponding transmission lines at points near the end thereof. In the case of the feed train e. g. such instrumentality is closely adjacent the hob whereby it is effective on the major portion of the transmission line and includes, in particular, the feed clutch 75 subject to considerable wear.

These important characteristics of elimination of back-lash and of fine adjustment, as conjointly and cooperatively related in the organization shown, serve to eliminate broken cutters, and damaged top gears, while at the same time permitting the cutter to be started close enough to the gear blank to ensure that the finishing cut will fall within a very close range. As a concomitant factor but little material need be left in the roughing operation for finishing purposes, with the result that the ultimate gear teeth will possess the perfection of proportion, uniformity and finish desired.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of United States:—

1. A non-differential hobbing machine combining a rotary tool spindle; a rotary work spindle, said spindles being relatively translatable to effect a feed; power transmission drive mechanism including branches for rotating said work spindle, rotating said tool spindle, and for effecting said feed, the drives for said rotary motions being unaffected by the drive for effecting said feed; means for manually rotating said hob reversely to its power drive to remove back-lash preliminary to a hobbing operation; a main feed clutch in said feed drive; an auxiliary fine-tooth clutch in said feed drive; and manually operative means connected in said feed drive to reverse said feed drive to remove back-lash with said fine-tooth clutch connected, and to independently effect said translatory motion when said fine-tooth clutch is disconnected to initially establish an accurate registration of the hob and gear preparatory to a hobbing operation.

2. A non-differential hobbing machine combining a rotary tool spindle; a rotary work spindle, said spindles being relatively translatable; power transmission drives to said spindles for effecting in timed relation said rotary motions and a feeding motion of translation; means for manually rotating said hob reversely to its power drive to remove back-lash preliminary to a hobbing operation; a main feed clutch in said feed drive; an auxiliary fine-tooth clutch in said feed drive; and

- manually operative means connected in said feed drive to effect said translatory motion.
3. A hobbing machine combining a rotary tool spindle; a rotary work spindle, said spindles being relatively translatable; power transmission drives to said spindles for effecting in timed relation said rotary motions and a feeding motion of translation; manually operative means for rotating said hob reversely to its power drive; a transmission drive for effecting translation at a rapid traverse rate; a main feed clutch in said feed drive; an auxiliary fine-tooth clutch in said feed drive; and manually operative means connected in said feed drive to effect said translatory motion.
4. A non-differential hobbing machine combining a rotary hob spindle; a rotary work spindle, said spindles being relatively translatable to effect a feed; a transmission drive for rotating said hob spindle; means located in said transmission near the hob end enabling the application at will of a manual device for operating said hob and its transmission in a direction reverse to the normal power operation; a transmission drive for rotating said work spindle; a transmission drive for effecting said feed, said transmission drives being associated for operation in timed relation; a main feed clutch in said feed drive; an auxiliary fine-tooth re-setting clutch in said feed drive and manually operative means connected in said feed drive to reversely operate said feed drive to remove back-lash with said fine-tooth clutch connected and to independently effect said translatory motion corresponding to the feed when said fine-tooth clutch is disconnected to initially establish an accurate registration of the hob and gear preparatory to a hobbing operation.
5. A non-differential gear cutting machine combining a work spindle; a cutter spindle; drive mechanism for rotating said work spindle; drive mechanism for rotating said cutter spindle; means for manually rotating said cutter spindle reversely to the normal drive; mechanism for effecting relative translation between said spindles; a feed clutch in said translatory mechanism; an auxiliary fine-tooth positive clutch in said translating mechanism; and means for manually effecting said relative translation when said fine-tooth clutch is disconnected.
6. A non-differential hobbing machine combining a primary source of power; a work spindle; a cutter spindle one of said spindles being translatable relative to the other; a transmission drive for rotating said work spindle; a transmission drive for rotating said cutter spindle; a transmission drive for effecting said translation, said drives being operable in timed relation; major clutch means for electively connecting or disconnecting the power drive through one of said transmission drives; an auxiliary fine-tooth positive clutch between said major clutch means and the corresponding spindle; and manual means connected in said transmission drive having said clutches therein between said auxiliary clutch and said corresponding spindle for removing back-lash from the corresponding transmission when said auxiliary clutch is connected and for manually effecting the corresponding drive when said auxiliary clutch is disconnected.
7. A hobbing machine of the non-differential type provided with means adapting it for re-cutting helicoidal gears combining a rotary work spindle; a rotary hob spindle, one of said spindles being translatable relative to the other; a transmission drive for rotating said hob spindle; manually operable means for reversely rotating said hob spindle preliminary to a hobbing operation to re-
- fecting said rotary and translatory motions in timed relation; selective means including a main feed clutch for rendering one of said drives effective independent of one or more of the other drives; an auxiliary fine-tooth positive clutch means in said independently effective drive; and a manual means connected in said last named drive and associated with said fine-toothed clutch for manually operating the corresponding drive.
8. A hobbing machine for re-cutting rough-cut helicoidal gears combining a rotary tool spindle; a rotary work spindle, said spindles being relatively translatable; associated power transmission drives to said spindles of the non-differential type for effecting in timed relation said rotary and translatory motions; positively engageable clutch means selectively operable for connecting or disconnecting said power translating drive from the other drives, said power translatory drive being associated with said other drives in such manner that the latter are unaffected in their rotary motion by the connection or disconnection of said translatory drive; and manually operative means for effecting a translatory adjustment when said power drive therefor is disconnected, said clutch means being constructed and the arrangement being such that said power drive may be re-established after said manual adjustment without disturbing the translatory position more than a few thousandths of an inch.
9. A hobbing machine adapted for finish cutting previously rough-cut helicoidal gears combining a rotary tool spindle; a rotary work spindle, said spindles being relatively translatable; a non-differential power transmission means including drives to said spindles for effecting in timed relation the rotations of said spindles and the relative translation thereof; the drives for said rotary motions being unaffected by said drive for producing relative translation; an auxiliary fine-tooth positive clutch in said translating drive; means for manually effecting said translation when said clutch is disconnected to bring the hob and gear into proper registration for initiation of the finishing cut, the arrangement being such and said fine-tooth clutch being so proportioned as to enable said clutch to be connected and the drive thereby established without disturbing the translated position beyond the limit of .010 of an inch or less.
10. A hobbing machine of the non-differential type adapted to finish-cut previously rough-cut helicoidal gears combining a rotary tool spindle; a rotary work spindle, said spindles being relatively translatable; power transmission drives to said spindles for effecting in timed relation said rotary motions and a feeding motion of translation; a main feed clutch in said feed drive; an auxiliary fine-tooth clutch in said feed drive between said main clutch and the corresponding spindle; manual feeding means between said fine-tooth clutch and said corresponding spindle, said manual means being effective for removing back-lash from the feed drive including said main clutch when said fine-toothed clutch is engaged, and effective for adjusting the hob into close registration with the gear when said fine-tooth clutch is disengaged.
11. A non-differential hobbing machine combining a rotary work spindle; a rotary hob spindle, one of said spindles being mounted for translation with respect to the other; a transmission drive for rotating said hob spindle; manually operable means for reversely rotating said hob spindle preliminary to a hobbing operation to re-

- move back-lash; a transmission drive for rotating said work spindle; a transmission drive for feeding said translatable spindle, said drives being associated for operation in positive timed relation but the drives for said rotary motions being unaffected in their timed relation to each other by said feed drive; a transmission means for independently translating said translatable spindle at a rapid traverse rate; a fine-tooth clutch in said feed transmission positioned therein near the spindle end of the transmission; and a manual operating means for said feed connected in said feed transmission between said fine-tooth clutch and the corresponding spindle for closely adjusting the relative positions of the hob and gear with respect to each other, said manual means enabling the operator to remove back-lash from said feed transmission when said clutch is engaged, and said fine-tooth clutch and the arrangement enabling the power feed drive to be established after said adjustment without departure from the pre-established relation with respect to said rotary drives within the limits permitted by material for a thin finishing cut.
12. A hobbing machine adapted for finish cutting previously rough-cut helicoidal gears combining a rotary hob spindle; a rotary work spindle provided with means for clamping a gear blank thereon; means for effecting a relative feed between said spindles; transmission drive trains for each of said spindles and for said feeding operation; main feed clutch means for said feed train; an auxiliary fine-tooth re-setting clutch in said feed train between said main feed clutch means and the termination of said feed train; means for manually operating said feed train in a direction reverse to the normal power drive from a point near its termination when the machine is idle to thereby remove back-lash; means for manually disconnecting said fine-tooth re-setting clutch, said manually operative feed means being thereby rendered available for independent manual adjustment whereby a closely adjusted initial registration of the hob and gear blank may be effected preliminary to the automatic cutting operation; and means for automatically driving said transmission drive trains at compatible speeds.
13. A hobbing machine adapted for finish cutting previously rough-cut helicoidal gears combining a rotary hob spindle; a rotary work spindle provided with means for clamping a gear blank thereon, said hob spindle being mounted for translation relative to said work spindle; transmission drive trains for rotating each of said spindles; a transmission drive train for translating said hob to effect a feed; means for automatically driving said transmission trains at compatible speeds for a cutting operation; a main feed clutch means; an auxiliary fine-tooth re-setting clutch in said feed train near its termination; means in said feed train for manually effecting a translation of said hob when said re-setting clutch is disengaged and permitting manual operation in the reverse direction to remove back-lash from said feed train when said re-setting clutch is engaged; and means for manually disconnecting said fine-tooth re-setting clutch after the back-lash has been removed from said feed train to permit thereafter the manual feeding of said hob whereby a closely adjusted registration of said hob and gear blank may be effected preliminary to the initiation of the automatic cutting operation, said fine-tooth clutch permitting re-establishment of the feed drive for automatic operation without material disturbance of the previous setting consistent with the allowance of metal on the gear blank for a re-cutting operation.
14. A hobbing machine adapted for finish cutting previously rough-cut gear blanks combining a rotary hob spindle; a rotary work spindle provided with means for clamping a gear blank thereon; means for mounting one of said spindles for translatory feeding movement relative to the other; a transmission drive train for each of said rotary spindles, and for said feeding movement; means for automatically driving said transmission trains at compatible speeds; a main feed clutch in said feed transmission; an auxiliary fine-tooth re-setting clutch in said feed transmission; means for manually operating said feed train in a reverse direction from a point near its termination, said manual operating means affording means for removing back lash in said feed train when said re-setting clutch is in engagement; and means for manually disconnecting said auxiliary re-setting clutch after the back-lash has been removed from the feed train to permit manual feeding whereby a closely adjusted registration of the hob and gear blank may be effected preliminary to the cutting operation, said fine-tooth clutch enabling reconnection of the feed drive for automatic cutting operation without disturbance of the initial manual setting beyond the close allowance of material on the gear teeth for a finishing operation.

WILLIAM F. ZIMMERMANN.
